UNITED STATES PATENT OFFICE.

PETER SHELLENBACK AND FERDINAND BRILMAYER, OF HAMILTON, OHIO.

IMPROVEMENT IN ROTARY BALANCED CUT-OFF VALVES.

Specification forming part of Letters Patent No. 136,622, dated March 11, 1873.

To all whom it may concern:

Be it known that we, PETER SHELLENBACK and FERDINAND BRILMAYER, of Hamilton, Butler county, Ohio, have invented certain Improvements in Rotary Balanced Cut-Off Valves, of which the following is a specification:

The first part of our invention consists of a rotary balanced cut-off valve, which is actuated by means of two bevel-wheels, one being fixed upon the crank-shaft of the engine, the other upon the valve-shaft.

Figure 1 is a partly-sectional side view of one valve, actuating bevel-gears and reverse motion. Fig. 2 is a front view of cylinder and valve-chests, showing the ports and also the flanges securing the valve-chest to the cylinder. Fig. 3 is an enlarged longitudinal section of the valve. Fig. 4 is a side view of the same.

a represents the bed-plate, upon which cylinder *B* is secured by screw-bolts. The valve-chest *c* is of cylindrical and conical shape, and is provided with flanges *r r*, by which it is secured to cylinder *B*, as shown in Fig. 1. The valve *d* is hollow, and so constructed as to fit the taper of the valve-chest *c* steam tight. The valve *d* is supported by and balanced upon the set-screw *f*, which is provided with a jam-nut, *j*, for the purpose of adjusting. The valve *d* is provided with two grooves, 3 and 4, the one, 3, communicating, through port 5, with space *w* of the valve *d*; the other, 4, through recesses 3, with the openings in cylinder *B* and exhaust-pipe of steam-chest *C*, shown in Figs. 1 and 3. Groove 3 also communicates with the induct-port 6 in the valve-chest. The steam enters the valve *d* at 6, as indicated by the arrow. The ports in the valve-chest

e are in line, as shown in Fig. 2. The ports *y y* in the valve *d* are in opposite ends of the valve, and therefore in revolving admit the steam alternately to cylinder *B*. The motion of valve *d* is attained by means of bevel-gears *x x*, one being secured on the crank-shaft of the engine, the other on the valve-shaft 10. The recesses communicating with groove 4 are set at opposite ends, as shown at *z z*, and the groove 4 communicates with exhaust-pipe in chest *C*. When port *y*, at either end of valve *d*, is admitting steam to cylinder *B* the recess *z* at the opposite end commences exhausting. The pinion on crank-shaft *q* is secured thereto by key or set-screw, and the pinion on the valve-shaft 10 is provided with a slot, *i*, so as to allow the sleeve *o*, which is secured to the valve-shaft by means of set-screw *t*, to partly turn.

It will be seen that by turning the valve-shaft, by means of hand-wheel 8, to either end of the slot *i* in the hub of pinion *ff*, the lead of the valve will be changed and the motion of the engine reversed. Valve *d* is closed on both ends, and, if found desirable, a stuffing-box may be applied to the valve-chest *c*.

We claim—

The hollow rotary balanced cut-off valve *d* having induct-ports *y y* and exhaust-ports *z z*, in combination with valve-shaft 10, bevel-wheels *ff*, and hand-wheel 8, all constructed and arranged for operation, substantially as and for the purposes set forth.

PETER SHELLENBACK.
FERDINAND BRILMAYER.
